UNITED STATES PATENT OFFICE.

THOMAS ELLIS AND OTTO HENRY ZERRMANN, OF DETROIT, MICHIGAN.

CRUDE-OIL BURNER.

Application filed January 29, 1920. Serial No. 354,779.

To all whom it may concern:

Be it known that THOMAS ELLIS and OTTO HENRY ZERRMANN, citizens of the United States of America, residing at Detroit, in the county of Wayne and State of Michigan, have invented new and useful Improvements in Crude-Oil Burners, of which the following is a specification.

The object of the invention is to provide a relatively simple and efficient burner adapted for the consumption of crude oil as a fuel in connection with boiler furnaces and the like and having means for regulating with facility the richness of the mixture or the relative proportions of oil and air or its equivalent combustion supporting agent to fulfill the requirements of the burner and suit the characteristics of the particular fuel which is in use, and to this end the invention consists in a construction and combination of parts of which a preferred embodiment is shown in the drawing, it being understood that changes in form and proportion may be resorted to within the terms of the claims without departing from the principles involved.

In the drawings:

Figure 1 is a side view of the burner.

Figure 2 is a longitudinal sectional view 30 of the same.

Figure 3 is a rear end view.

Figure 4 is a front end view showing the locking device in section.

The burner consists essentially of a shell 35 10, preferably cylindrical in form, upon which is adjustably fitted a nozzle 11 having a porcelain or equivalent refractory lining 12 of which the inner end is enlarged as shown at 13 to snugly fit the bore of the 40 shell, said lining thus serving to define a cylindrical outlet 14 having an inner tube or funnel-shaped mouth 15 into which projects the exteriorly tapered or conical fuel discharge nipple 16 supported by webs 45 17 in the main shell or casing 10. Connected with this nipple and disposed axially in the shell or casing is the feed pipe 18 fitted at its rear end with a removable plug 19 to facilitate cleaning the nipple to 50 remove any gummy or other accumulations in the outlet thereof, and in communication laterally with the feed tube is the supply pipe 20 for the fuel, extending through a suitable stuffing box 21 supported by the 55 wall of the shell or casing. Inferiorly at its rear end the shell or casing is preferably

threaded as at 22 for attachment to a suitable pipe (not shown) by which the combustion supporting agent such as air, steam or the equivalent thereof may be supplied. 60

The shell of the nozzle is adjustably mounted upon the casing 10 as by means of a fast screw 23 or the equivalent thereof and attached to said shell and extending radially therefrom is a handle or grip 24 65 in which is mounted a latch bolt 25 actuated by a spring 26 and adapted for engagement with a rack 27 disposed obliquely upon the exterior surface of the casing, said latch preferably having a tapered or conical rack-70 engaging nose 28 to adapt it to slip from one tooth to another of the rack as the nozzle is turned to vary its adjustment, but serving under normal conditions, or when pressure is not exerted upon the grip or handle 24, 75 to hold said nozzle in its adjusted positions. The axial movement of the nozzle relative to the fuel outlet nipple, owing to the co-operative relation of the funnel-shaped inlet of the passage 14 in the nozzle and the 80 tapered or conical form of the nipple, serves to vary the area of the annular passage defined by said funnel-shaped inlet and conical nozzle, to regulate the supply of the combustion supporting agent to the passage 85 in the nozzle to suit the conditions under which the burner is being used and the peculiarities of the fuel which is employed.

What is claimed is:

1. A crude oil burner having a cylindrical casing provided at its rear end with an inlet for a combustion supporting agent, a fuel feed tube disposed axially in the casing and provided with an exteriorly conical discharge nipple, a nozzle having a shell 90 adjustably mounted upon the casing by a fast threaded connection to provide for longitudinal movement of the nozzle with respect to the casing, and a handle or grip carried by the nozzle and provided with a yielding latch, the casing being provided with means for engagement by said latch to preclude relative movement of the nozzle and casing after adjustment of the latter. 95

2. A crude oil burner having a cylindrical casing provided at its rear end with an inlet for a combustion supporting agent, a fuel feed tube disposed axially in the casing and provided with an exteriorly conical discharge nipple, a nozzle having a shell 100 adjustably mounted upon the casing and having a fast thread connection 105

therewith, said nozzle being provided with a refractory lining in axial alignment with the discharge nipple and provided with a funnel-shaped inlet disposed concentrically with relation to said nipple, a rack arranged obliquely upon the casing, and a nozzle adjusting handle or grip carried by the shell

of the nozzle and provided with a yielding latch for engagement with said rack.

In testimony whereof they affix their signatures.

THOMAS ELLIS.

OTTO HENRY ZERRMANN.
